UNITED STATES PATENT OFFICE.

JOHN HUBENY, OF ELIZABETH, NEW JERSEY, ASSIGNOR TO HUBENY BROS., A CO-PARTNERSHIP COMPOSED OF JOSEPH HUBENY, JEREMIAH HUBENY, ANTHONY HUBENY, AND JOHN HUBENY, ALL OF ELIZABETH, NEW JERSEY.

SCAFFOLD BRACKET.

Application filed October 24, 1925. Serial No. 64,663.

To all whom it may concern:

Be it known that I, JOHN HUBENY, a citizen of the United States, and a resident of Elizabeth, in the county of Union and State of New Jersey, United States of America, have invented a new and Improved Scaffold Bracket, of which the following is a full, clear, and exact description.

Objects of the present invention are to provide a scaffold bracket which may be readily attached to and detached from the wall of a building, a bracket which is of simple, practical and rugged construction, which will be readily held against side sway or wobble when hung, which is adjustable to various widths of studding, which can be folded so that it will occupy a very small space when not in use, and which may be manufactured with comparative economy.

A more specific object of the invention is to avoid the usual disadvantages of scaffold brackets formed of pipe sections with flattened ends, by equipping the ends of all of the bracket arms with malleable castings to eliminate breakage and distortion, and thereby prolong the life of the bracket.

With the above noted and other objects in view the invention consists in certain novel features of construction and combinations and arrangements of parts, as will be more fully hereinafter set forth and pointed out in the claim. The invention may be more fully understood from the following description in connection with the accompanying drawings, wherein—

Fig. 1 is a perspective view of a bracket in applied position.

Fig. 2 is an enlarged plan view showing the bracket folded.

Figs. 3 and 4 are sectional details on the lines 3—3 and 4—4 respectively of Fig. 1.

Fig. 5 is an enlarged perspective view of a pair of associated castings.

Fig. 6 is an elevational detail showing the connection of the adjustable arms and the diagonal bracing member.

The bracket includes a pair of arms 10 preferably of flat steel stock having keyhole slots 11 in their upper ends, through which nails are adapted to be driven to support the bracket on the wall of a building. Arms 10 are slightly angular, so that their upper ends will be approximately parallel when the two arms are spread to fully extended

position. The lower ends of the arms are 55 twisted as indicated at 12, and pivotally connected at 13 to the flattened end 14 of a malleable casting 15 which includes a socket into which the lower end of a diagonal bracing arm 16 may be screwed. The 60 twist in the lower ends of the arms 10 provides sufficient flexibility so that their upper ends may be spread varying distances apart in accordance with the distance between studding in the walls to which the brackets 65 may be attached.

The intermediate portions of brackets 17 straddle offset portions 18 in the upper ends of the arms 10, and are preferably riveted thereto as indicated in 19. Brackets 17 provide pairs of forwardly presented arms 20 between which the flattened ends 21 of castings 22 are pivotally secured upon pins 23. The castings 22 are also formed with suitable threaded sockets for the reception of 75 arms 24, adapted to be supported in horizontal position by the diagonal brace 16. It is upon the arms 24 that the planking or scaffolding is laid. I prefer to form the brace 16 and the arms 24 of steel pipe. The 80 free end of one arm 24 is secured in a casting 25 similar to casting 22, and the free end of the other arm 24 is received in a socket 26 integral with a casting which includes a flat plate 27, having a slot 28 and hole 29 85 therein. The opening 29 is adapted to register with an opening 30 in the casting 25, said aligned openings accommodating a pivot pin 31.

A casting 32 at the free end of the diagonal brace 16 includes a shoulder portion 33 and an angularly disposed tongue 34 projecting above the shoulder. The tongue 34 is adapted to pass through the slot 28 in the plate 27, so that the plate will rest upon the shoulder 33, and the arms 24 will be rigidly supported by the diagonal brace.

The manner of folding or collapsing the bracket is apparent from Fig. 2 wherein it will be noted that the arms 24 have been disconnected from the diagonal brace by lifting the plate 27 off the shoulder 33. The arms 24 are then swung downwardly on their pivots 23. The brace 16 is swung upwardly on its pivot 13, and the flexibility of the twisted lower ends of the arms 10 permits their free ends to be moved together.

From the foregoing it will be evident that

I have provided a bracket which is rigidly supported in applied position ~~against~~ side sway or wobble, which may be quickly applied or detached, and which is well adapted
5 for withstanding the rough usage to which it is ordinarily subjected.

The provision of the castings 15, 22, 25, and the casting which includes socket 26 and plate 27 greatly prolongs the life of the bracket. It has been heretofore customary, simply to flatten the ends of the pipes which formed the bracket arms, and pivotally connect such flattened ends together, with the result that breakage and distortion frequently occurred at the pivots.

While I have illustrated a preferred embodiment of the invention, various slight

changes and alterations might be made within the spirit and scope of the appended claim.

20

I claim:—

A scaffold bracket including a pair of horizontal tubular arms, castings formed with sockets into which the ends of the arms are screwed, supporting members adapted to be attached to a wall means for pivotally connecting the castings at one end of the arms to the supporting members, means for pivotally connecting the castings at the free ends of the arms together, and means engageable with said connecting castings for supporting the arms in horizontal position.
